UNITED STATES PATENT OFFICE.

EDWARD T. PARDEE, OF BOSTON, MASSACHUSETTS.

VALVE-CONTROLLING DEVICE.

941,033.

Specification of Letters Patent. Patented Nov. 23, 1909.

Application filed May 8, 1907. Serial No. 372,584.

To all whom it may concern:

Be it known that I, EDWARD T. PARDEE, a citizen of the United States, residing at Boston, county of Suffolk, and State of Massachusetts, have invented an Improvement in Valve-Controlling Devices, of which the following description, in connection with the accompanying drawing, is a specification, like numerals on the drawing representing like parts.

This invention has for its object to provide a novel valve controlling means which is especially adapted for controlling the valve in a gas pipe or conduit leading to gas burners in a railway car.

Whenever an accident occurs on a railroad and a passenger car is overturned, one of the greatest dangers is from fire caused by the ignition of inflammable parts of the car, as its furnishings, or of escaping gas.

The primary object of my invention is to provide a novel valve device controlling the supply of gas to the burners which will be held open so long as the car is upright, but which will be automatically closed if the car should be overturned, thereby shutting off the supply of gas to the burners and preventing any danger of fire.

In accordance with my invention, I provide a valve in the gas conduit and a device for holding the valve open, which device is maintained in its operative position by gravity so long as the car is upright, but which is thrown out of its operative position when the car turns over and permits the valve to close.

In the drawings wherein I have shown one embodiment of my invention, the gas pipe or conduit 3 has therein a valve passage 4 within which is a suitable valve 5. The valve is shown as provided with a stem 6 which extends through the casing and preferably through a suitable packing box 7. Within the valve casing is shown a suitable spring 8 which normally tends to close the valve. The valve may be of any suitable shape or construction, and I have herein shown it as an ordinary piston-valve, although this is not essential to my invention. The valve is normally held open by a suitable strut or restraining device 9 which is held in its operative position by gravity. This strut 9 is shown as having an enlarged portion 10 which rests on a suitable support 11, and the end of the strut bears against

the head 12 of the valve stem. The strut has depending therefrom the weighted pendant 13 which acts to hold the strut normally in its operative position, as shown in the drawings. If for any reason the strut 60 is thrown out of its vertical position so as to be disengaged from the head 12, then the spring 8 will come into play to close the valve 5, as will be obvious.

When this invention is used in connection 65 with the gas piping system of a railway car, a valve as herein shown may be placed in the gas pipe or conduit leading from the gas reservoir to the burners, or a valve may be placed in each pipe at a point between the 70 main conduit and each burner. In either event so long as the car is in its vertical position after the device is properly adjusted, the weighted pendant 13 will hold the strut 9 in its operative position to maintain the valve open, but if for any reason the car turns over on to its side or tips sufficiently so that the action of gravity on the pendant 13 will swing the strut 9 clear from the head 12, then the spring 8 will come 80 into play to close the valve automatically and shut off the supply of gas. The head 12 is herein shown as having a concave under face 14 against which the strut 9 rests. The amount which the car may tip before 85 the valve will be closed depends on the size of the face 14, as will be obvious. Since the car of a rapidly-moving train always has more or less motion, it is desirable that the surface 14 should have sufficient size to 90 allow for all ordinary vibrations or swinging movement of the pendant without danger of becoming disengaged from the head 12.

In the present embodiment of my invention the enlarged portion 10 of the strut is made rounded so that it can easily turn in any direction on the support 11, and the pendant 13 hangs down through said support. This, however, is only the preferred 100 embodiment of the invention, and I do not wish to be limited thereto.

In order to avoid ambiguity, I will refer to the proper vertical position of the valve and pendant weight as shown in the drawings as the normal position, and that position which the valve and pendant weight must assume relative to each other in order to permit the valve to close, as the abnormal position.

Having fully described my invention, what I claim as new and desire to secure by Letters Patent is:—

1. The combination with a gas conduit, a valve body connected thereto and a valve within the valve body, of a support adjacent the valve body, gravity-actuated means sustained by the support to maintain the valve open when the valve and support are in normal position, said gravity-actuated means being moved by gravity out of its operative position when the support and the valve are moved into abnormal position, whereby the valve is permitted to close, and automatically-operative means to close the valve when released by said gravity-actuated means.
2. The combination with a gas conduit and valve therein, of a strut to hold the valve open, gravity-actuated means to maintain the strut in operative position when the valve is in normal position and to cause said strut to be disengaged from the valve when the latter is turned sufficiently out of its normal position, and means to close the valve when released by the strut.

3. The combination with a gas conduit, of a spring-pressed valve for closing the conduit, means maintained in a given position by gravity and adapted to hold said valve open against the action of the spring when the valve has a certain position relative to said means and to release said valve thereby permitting the valve to close when the valve has another position relative to said means.

4. The combination with a gas conduit, of a spring-actuated valve for closing the same, a strut for holding said valve open against the action of the spring, a support for the strut, and a pendant weight associated with said strut and depending below said support whereby the weight keeps the strut in vertical position.

In testimony whereof, I have signed my name to this specification, in the presence of two subscribing witnesses.

EDWARD T. PARDEE.
